UNITED STATES PATENT OFFICE.

SAMUEL M. LANGSTON, OF WENONAH, NEW JERSEY.

CUT-OFF MECHANISM FOR SHEET MATERIAL.

1,176,574.

Specification of Letters Patent. Patented Mar. 21, 1916.

Application filed September 13, 1915. Serial No. 50,338.

To all whom it may concern:

Be it known that I, SAMUEL M. LANGSTON, a citizen of the United States, and resident of Wenonah, in the county of Gloucester and State of New Jersey, have invented certain new and useful Improvements in Cut-Off Mechanisms for Sheet Material, of which the following is a specification.

10 This invention relates to certain improvements in cut-off mechanisms for comparatively stiff material, such, for instance, as double-faced corrugated paper.

The main object of my invention is to permit of the more economical cutting of such material than is possible with machines now in use. Due to the fact that double-faced corrugated paper cannot be rolled, folded, or bent to any appreciable extent without breaking down the structure, it is necessary to sub-divide it into sections as it leaves the machine in which it is manufactured. The cutting mechanism is usually so regulated that these sections are of the same length, or a multiple of the length of the final product. Such machines may be economically used when the width of the sheet is approximately the same as the width of the final product or a multiple of such width. If the final product is to be of a width, for instance, slightly more than one-half the width of the sheet as it comes from the manufacturing machine, the sheet must be cut across the full width in dividing it into sections and must be slitted lengthwise to give the desired width, the latter operation being either before or after cross-cutting. This leaves narrower sections of the same length as the wider sections but possibly not suited for economical cutting to fill some other order requiring smaller sheets.

I am aware that machines have been designed for simultaneously slitting thin paper into strips and cutting the separate strips into sections of different lengths, but such machines are not suitable for use with double-faced corrugated paper, due to the fact that the latter cannot be bent as has been previously stated.

50 By means of my improved machine, I am able to slit the sheet into strips of any desired width and sub-divide each of these strips into sections, the length of the sections formed from one strip being independent 55 of the length of the sections formed

from any other strip. To secure this object, I arrange a plurality of independently governable cut-off mechanisms and design them, or at least all except the last one, so that only one strip or the desired number of strips will be cut off as the entire sheet passes therethrough.

In the accompanying drawings I have illustrated two different forms which my invention may assume, but it will be evident that other forms may be designed within the spirit of my invention and without departing from the scope of the appended claims.

In these drawings, to which reference is to be had and in which similar reference characters indicate corresponding parts in the several views, Figure 1 is a top plan view of one machine embodying my invention; Fig. 2 is a side elevation; Fig. 3 is a top plan view of a second form; and Fig. 4 is a side elevation of the form shown in Fig. 3.

In the form illustrated in Figs. 1 and 2, I have shown a delivery mechanism 10 which may be either a part of the machine for making the double-faced corrugated paper, or a mechanism receiving the paper from the machine and delivering it to the cut-off mechanism. The delivery mechanism is illustrated as including two belts having superposed parallel runs for engaging with opposite sides of the sheet —A— and advancing the latter.

Beyond the delivery mechanism I mount 90 suitable slitting mechanism for sub-dividing the sheet into a plurality of separate strips. This slitting mechanism may be of any suitable character, such, for instance, as rotary overlapped cutters 11 and 12 mounted on parallel shafts. The cutters may be adjusted lengthwise of the shafts to vary the relative widths of the strips and any desired number of cutters may be employed for subdividing the sheet into a large number of 95 strips.

Merely for purposes of illustration, I have shown a single pair of slitters subdividing the sheet into strips —B— and —C— and have illustrated said slitters as 105 being driven by a pair of intermeshing pinions, one of which meshes with a gear on the shaft of one of the drums of the delivery mechanism. I do not desire to be limited to any particular kind of slitting 110

mechanism or any particular method of driving or operating the same as any corresponding parts known in the trade may be employed.

5 Mounted beyond the slitter, I provide a plurality of independently governable cut-off mechanisms operating in substantially the same plane as the plane of delivery of the sheet —A—. Each transverse cutter is 10 illustrated as including a base 13 supporting a stationary knife 14 and a movable knife 15 for coacting therewith to perform the cutting operation. Each blade extends the full width of the sheet so that the sheet 15 may be cut all the way across by either cut-off mechanism. Each stationary knife is comparatively narrow and its base is provided with a slot extending the entire width of the sheet so that the entire sheet 20 may pass through the slot beneath the stationary knife and pass the cut-off mechanism unaffected by the latter, if desired.

The movable knives 15 may be operated in any suitable manner and may be of any 25 desired character. Preferably they are carried by shafts 16 and are mounted to rotate so as to coact with the stationary cutter once during each revolution. The driving mechanism is such that the speed and 30 movement of each movable knife may be varied in respect to the speed of the other knife or knives and in respect to the rate of delivery of the sheet from the mechanism 10.

I have illustrated two cut-off mechanisms, 35 each driven by a belt 17 which receives its power from the delivery mechanism or from some source of power connected to the latter so that the speed of the cutters may be directly dependent upon the speed of delivery 40 of the material. The mechanism for transmitting power to each rotary cutter includes some form of speed varying device which may be of any well-known character. I have illustrated rather conventionally one 45 form of such mechanism which includes a friction disk 18 and a friction wheel 19 adjustable along the face of the disk toward and from the center to vary the speed of the driving belt 17. This form of mechanism 50 will operate to rotate the cutters continuously, but permit the speed of either cutter to be varied in respect to the other and the speed of both to be varied in respect to the rate of delivery of the material. In actual 55 practice, I prefer to use a cutter controlling mechanism which permits the movable cutter to remain stationary until the controlling mechanism comes into play to give the cutter a single revolution. The controlling 60 mechanisms of the different cutters may be adjusted to operate them at different frequencies and may include trip mechanism operated by the material itself. Such a mechanism is illustrated in my copending 65 application Serial No. 58,174, filed October

27, 1915, but forms no portion of my present invention and therefore has not been here illustrated.

In operation, the sheet —A— as it leaves the feeding mechanism is slit into separate strips the width of at least one of which is regulated in accordance with the width of the final product, and the two or more separate strips are delivered in approximately the same plane to the first cut-off mechanism. One or more of the strips passes over the stationary knife 14 so as to be operated upon by the movable knife 15, while the other or others are deflected slightly so as to pass through the slot in the support for the 70 stationary knife 14. As illustrated, the strip —C— passes beneath the stationary knife while the strip —B— passes there-over. The separate sections of the strip —B—, if they are comparatively short, may 75 be received by any suitable mechanism between the two cut-off mechanisms and conveyed laterally or stacked up, or merely permitted to fall to the floor. If the sections are longer than the distance between the 80 cut-off mechanisms, the sections of the strip —B— may pass through the slot beneath the stationary knife 14 of the second cut-off mechanism, as illustrated.

It will be noted that the strip —C— passes 95 directly through the first cut-off mechanism without being sub-divided and is deflected upward slightly so as to pass over the stationary knife of the second cut-off mechanism.

100 By proper regulation of the machine, the separate strips may be made of different widths in accordance with the dimensions of different desired products and each strip may be sub-divided into sections, the length 105 of the sections of one strip being independent of those of the other.

In Figs. 3 and 4, I have illustrated a slightly modified form of cut-off mechanism whereby the same results may be secured. In this form, the stationary knives 14^a, instead of having slotted supporting portions through which the material may pass, are adjustable endwise so as to be capable of assuming positions beneath only a 110 portion of the width of the sheet. Each stationary knife 14^a is illustrated as having a supporting portion 20 mounted in a dovetailed groove in the base 13^a. The movable knives 15 extend the full width of the sheet 115 and the stationary knives are each of a length equal to the total width of the sheet. With two cut-off mechanisms in operation, one stationary knife 14^a may be moved out endwise so that it lies beneath one strip of 120 the sheet and terminates at the slit between the strips while the other stationary knife extends out endwise in the opposite direction and also terminates at the slit. In some machines, I might arrange the movable 125 130

knife so as to permit of its endwise adjustment instead of adjusting the stationary knife but the arrangement illustrated is simpler and preferable. If the sheet be subdivided into three (3) strips, the outer strip on one side might be cut off by the first cut-off mechanism, the other strip by the next cut-off mechanism, and the center strip by a third cut-off mechanism in which the knives 10 need not be endwise adjustable. Other arrangements might be readily made for a larger number of strips. Thus the strips may be fed through the machine and the separate strips cut off into sections of different lengths.

Having thus described my invention, what I claim as new and desire to secure by Letters Patent is:

1. A machine for sub-dividing comparatively stiff sheet material, including sheet delivering mechanism, slitting mechanism for sub-dividing the sheet lengthwise, and a plurality of cut-off mechanisms separate from and arranged beyond said slitting mechanism and each operating on a separate strip of said sheet and permitting the passage of another strip therethrough in approximately the same plane.

2. A machine for sub-dividing comparatively stiff sheet material, including sheet delivering mechanism, slitting mechanism for sub-dividing the sheet lengthwise, and a cut-off mechanism including a stationary knife and a movable knife, one knife being constrained to operate on only one strip of said sheet and permit the passage of another strip therethrough in approximately the same plane.

3. A machine for sub-dividing comparatively stiff sheet material, including sheet delivering mechanism, slitting mechanism for sub-dividing the sheet lengthwise, and a cut-off mechanism operating to sub-divide one strip transversely, said mechanism including a stationary knife constructed to operate on only one strip, and permit the passage of another strip and a movable knife cooperating therewith.

4. A machine for sub-dividing comparatively stiff sheet material, including sheet delivering mechanism, slitting mechanism for sub-dividing the sheet lengthwise, and a plurality of cut-off mechanisms arranged in succession beyond said slitting mechanism and each including a stationary knife arranged to operate on only one strip and permit the passage of another strip in approximately the same plane and a movable knife cooperating with the stationary knife.

5. A machine of the class described, including means for delivering a plurality of strips of comparatively stiff sheet material in approximately the same plane, and two independently controllable cut-off mechanisms operable in the same plane and ar-

ranged in succession, one serving to subdivide one strip and permit the passage therethrough of a second strip and another serving to subdivide a third strip.

6. A machine of the class described, including means for delivering a plurality of strips of comparatively stiff sheet material in approximately the same plane, two cut-off mechanisms operable in the same plane and arranged in succession, one serving to subdivide one strip and permit the passage therethrough of a second strip and another serving to subdivide said second strip, and means for independently controlling said cut-off mechanisms to subdivide the separate strips into sections of different lengths.

7. A machine of the class described, including means for delivering a plurality of strips of comparatively stiff sheet material in approximately the same plane, and a cut-off mechanism including a comparatively narrow stationary knife, a support therefor constructed to permit the passage of one or more strips directly beneath said stationary knife, and a movable knife cooperating with said stationary knife to subdivide the strip or strips passing above the latter.

8. A machine of the class described, including means for delivering a plurality of strips of comparatively stiff sheet material in approximately the same plane, and a plurality of cut-off mechanisms arranged in succession and operating in substantially the same plane and each including a comparatively narrow stationary knife, a support therefor, constructed to permit the passage of one or more strips directly beneath said stationary knife, and a movable knife cooperating with said stationary knife to subdivide the strip or strips passing above the latter.

9. A machine of the class described including sheet delivering mechanism, slitting mechanism for sub-dividing the sheet lengthwise, independent cut-off mechanisms operating upon the separate strips and each cutting the material in substantially a straight line from the slitting mechanism, and independent controlling mechanisms for said cut-off mechanisms whereby sections of different lengths may be cut off by the different cut-off mechanisms.

10. A machine of the class described including sheet delivery mechanism, slitting mechanism for sub-dividing the sheet lengthwise, and a cut-off mechanism including a comparatively narrow member having one edge substantially in the plane of delivery of the sheet and a transversely extending rotary member for cooperating with the first mentioned member to sub-divide the sheet transversely, and a support for said first mentioned member constructed to permit the passage of one or more strips from said slitting mechanism approximately in the same

plane but on the opposite side of said first mentioned member from said rotary member.

11. A machine of the class described including means for delivering a sheet of double faced corrugated paper, a slitting mechanism for sub-dividing said sheet lengthwise and a cut-off mechanism including a transversely extending rotary cutter, and a transversely extending member coöperating therewith, said member being comparatively narrow and permitting the passage of one or more strips from the slitting mechanism upon one side thereof and one or

more strips upon the opposite side thereof without deflecting any of said strips to any considerable extent from the plane of delivery whereby only certain of said strips may be acted upon by said rotary cutter.

Signed at Camden in the county of Camden and State of New Jersey, this 7th day of 20 September, A. D. 1915.
